UNITED STATES PATENT OFFICE.

BERNARD A. STERLING, OF CHICAGO, ILLINOIS.

FASTENING DEVICE.

Application filed February 24, 1925. Serial No. 10,993.

My invention relates to an improved fastening device more particularly for use with hair dressing attachments and the like, and its objects are the provision of a device which is adapted to be positively locked upon the hair and which will firmly grip the hair and be held in place thereon, and a simple and improved structure that may be economically produced, one that may be quickly and conveniently secured in place and removed and which will not cause any discomfort when in place.

The invention is illustrated in the accompanying drawings, in which:

15 Figure 1 is a front elevational view of a device embodying the invention;

Figure 2 is a top plan view of the same showing the end of a hair piece attached thereto;

20 Figure 3 is a back or rear elevational view;

Figure 4 is a transverse section on line 4—4 of Figure 3;

25 Figure 5 is a transverse section on line 5—5 of Figure 3, and

Figure 6 is a front elevational view showing the use of the device of my present invention.

The embodiment of the invention shown 30 comprises a base or bar 5 and a prong 6 pivoted at 7 in the bifurcated end 8 of a block 9 rigidly or fixedly secured to the back of the bar 5.

The bar 5, prong 6 and block 7 may be 35 of celluloid, tortoise or other suitable material and they may, of course, be colored to match or harmonize with the hair with which the device is to be used. The rigid attachment of the block 9 to the back of the bar 5 may be through rivets 12 and the pivot 7 may comprise a pin inserted through 40 the bifurcated ends of the block 9 and passing loosely through the pivoted end of the prong 6.

45 The bar 5, may be curved to conform generally to the head. The bar 5 is shown as converging in opposite directions from the portion to which the block 9 is secured. One reduced end is turned laterally at substantially right angles at 14 and notched at 15 to form a latch or hook into engagement with which the free end of the prong 6 is adapted to be sprung, the catch interlocking with the prong and locking the same closed so that when the attachment is placed upon the head and the clasp closed,

the device will be firmly and positively secured or clamped to the user's hair and held against accidental displacement.

In use, the device is inserted up into 60 the hair with the back side presented to the head and the prong opened to permit a mass of hair strands to pass between the back of the bar 5 and prong 6. The prong 6 is then swung into closed position and 65 the free end thereof is sprung up over the hook 15 and into engagement therewith whereupon the strands of hair are clamped between the bar 5 and prong 6.

Secured to the back or rear surface of 70 the bar 5 and underlying the prong 6 is a strip of anti-slip substance or material 20 such as rubber, rubber fabric, fabric or the like. The strip 20 may be glued or otherwise firmly secured upon the back of 75 the bar 5 and it extends longitudinally of the prong and opposite thereto. When the prong is closed upon the strands of hair, said strands are clamped against the strip 20 and between said strip 20 and the prong 80 6. The strip 20, because of its yieldable and anti-slip character, binds the strands of hair firmly and positively and prevents accidental slipping of the device after it is attached to the hair.

85 While the device may be employed wherever found desirable, it is particularly adapted for use with hair dressing attachments of the type shown and described in my co-pending application Serial No. 9,397, filed February 13th, 1925. The spacing of the block 9 and point of pivoting of the prong 6 from the end 22 of the bar 5 provides a space for transversely arranged rows of apertures 24 through which wefted end 25 of the hair piece 26 may be secured to the bar 5, as by stitching 27 passing through the apertures 24 and stitched to the wefted end of the hair piece or to the stitches wefting the strands of hair of said end together. Rearwardly of the apertures 24, the bar 5 has a transversely elongated slot 28 through which a band 50 connecting two fastening devices of this sort in the manner of my above referred to application may be looped, doubled back and secured as by stitching or in any other suitable manner, as shown in Fig. 6.

100 The hooked end of the bar 5 is recurved at 30 and the free end of the prong 6 which 105 prong is shown as being curved to conform to the back of the bar 5 is also preferably re-

curved at 32. This removes the free end of the prong 6 from possible pricking engagement with the head when the device is in place thereon and avoids any discomfort to the head at this end. The spacing of the block 9 from the opposite end in addition to providing a space for the slot 28 and apertures 24, performs the additional function of removing the block and pivoted end of the prong 6 from the end of the bar, thereby eliminating any pressure or discomfort on the head.

While this, of course, may be varied, the block 9 is preferably mounted at an angle, as shown to incline the prong 6 normally downwardly slightly so that upon springing the prong into the hook 15, this downward inclination and the slight bind produced at the pivot 7 will hold the prong 6 firmly in locked position.

While I have shown and described the anti-slip strip 20 as being secured to the base member 5 it is to be understood that this gripping surface may be on the prong instead or cooperating gripping surfaces of this sort may be provided on both the base member 5 and on the prong 6.

The two transverse rows of apertures 24 are preferably arranged diagonally or obliquely with reference to the width of that portion of the bar or base member 5 through which they open. This spreads the ends of the strands of hair attached thereto longitudinally of the fastening device and facilitates distributing and arranging the hair piece 26 up in the desired position.

I claim:—

1. As an article of manufacture, a fastening device comprising, a base member having a catch at one end and slotted transverse-

ly at its opposite end for attachment to a fastening device, a prong swingable into and out of engagement with said catch, said prong having a base attached to the back of said base member and spaced from the slotted end thereof and means between the base member slot and the prong base for attaching a hair piece to said base member. 45

2. As an article of manufacture, a fastening device comprising, a base member having a catch at one end and slotted transversely at its opposite end for the attachment of a fastening device to the base member, a prong swingable into and out of engagement with said catch, said prong having a base attached to the back of said base member and spaced from the slotted end thereof. 50 55

3. In combination, a fastening device having a base member, said base member having a generally transverse row of apertures, said row of apertures being obliquely disposed in a transverse direction with respect to said base member and adapted for attaching a hair piece to said base member.

4. As an article of manufacture, a barrette comprising a base member having a catch at one end, means at the opposite end for attachment to a fastening device, a prong attached to said base member and swingable into and out of engagement with the catch, the attachment of said prong to said base member being spaced from the fastening means attachment end of the base member to provide a hair piece attaching portion between the fastening device attachment 70 75 and the prong attachment to said base member.

In witness whereof, I hereunto subscribe my name this 21st day of February, 1925.

BERNARD A. STERLING.
